WASTE RECEPTACLE

Ralph LaRue DuBois, 4242 E. 111th St.,
Tulsa, Okla. 35741

Filed Sept. 26, 1969, Ser. No. 19,303

Term of patent 14 years

Int. Cl. D7—06

U.S. Cl. D49—30

FIG. 1

FIG. 2

FIG. 3

FIG. 4

FIG. 1 is a front elevational view taken from one side of a waste receptacle showing my new design, the opposite side being substantially a mirror image thereof;

FIG. 2 is a side elevational view, the opposite side being substantially a mirror image thereof.

FIG. 3 is a top plan view;

FIG. 4 is a bottom plan view.

A portion of waste receptacle is stippled to indicate a contrast in appearance.

I claim:

The ornamental design for a waste receptacle, substantially as shown and described.
